(57) **CLAIM**

The ornamental design for a printer, as shown and described.

DESCRIPTION

FIG. 1 is a perspective view of a printer;
FIG. 2 is a front elevational view thereof;
FIG. 3 is a top plan view thereof;
FIG. 4 is a left-side elevational view thereof;
FIG. 5 is a right-side elevational view thereof;
FIG. 6 is a rear elevational view thereof;
FIG. 7 is a bottom plan view thereof;
FIG. 8 is a perspective view thereof showing an alternative position;
FIG. 9 is a front elevational view thereof showing the alternative position;
FIG. 10 is a right-side elevational view thereof showing the alternative position;
FIG. 11 is a detail view of the portion indicated as "11" in FIG. 8;
FIG. 12 is a detail view of the portion indicated as "12" in FIG. 9; and,
FIG. 13 is a detail view of the portion indicated as "13" in FIG. 10.
The evenly spaced broken lines depict unclaimed parts of the printer and form no part of the claimed design. The dot-dash chain lines forming rectangular shaped boxes around certain portions of FIGS. 8, 9 and 10 depict areas shown as detail views in FIGS. 11, 12 and 13, and form no part of the claimed design.
